UNITED STATES PATENT OFFICE.

JACOB F. BIXLER, OF KANSAS CITY, KANSAS, ASSIGNOR OF ONE-HALF TO JERRY
RELLIHAN, OF KANSAS CITY, KANSAS.

BASKET-COVER.

1,210,267.

Specification of Letters Patent. Patented Dec. 26, 1916.

Application filed April 17, 1916. Serial No. 91,707.

To all whom it may concern:

Be it known that I, JACOB F. BIXLER, a citizen of the United States, residing at Kansas City, in the county of Wyandotte 5 and State of Kansas, have invented new and useful Improvements in Basket-Covers, of which the following is a specification.

This invention is an improved cover for use on baskets and especially market baskets 10 and the like, the object of the invention being to provide an improved basket cover which is cheap and simple in construction, may be made of paper or other like material, and which may be compactly folded so as to 15 take up but little room when not in use and which can be manufactured at very small cost.

The invention consists in the features of construction, combination, and arrangement 20 of devices, hereinafter described and claimed.

In the accompanying drawings: Figure 1 is a perspective view of a basket cover constructed and arranged in accordance with 25 my invention and showing the same in use on a market basket of usual form provided with a centrally arranged handle. Figs. 2 and 3 are detail sectional views of the same. Fig. 4 is a plan of the blank from which the 30 cover is made.

My improved basket cover 1, may, in practice, be made of paper of suitable thickness, or of any other suitable flexible material. The cover is made from an oblong rectangular blank 2 which is folded on longitudinal lines 3 to form sides 4 and is also folded on transverse lines 5 to form ends 6. Slits 7 form longitudinal extensions of the fold lines 3 and extend from the lines 5 to the 35 ends of the blank and serve to divide the ends 6 from flaps 8 which are formed in the corners of the blank. The flaps may be folded on lines 9 which are coincident with the fold lines 5 so that said flaps may be arranged in overlapping relation on and secured to the outer sides of the ends 6. Hence, the ends 6 are connected to the sides 4 of the cover by the flaps 8 and are also reinforced by said flaps. Diagonal fold lines 40 10 are arranged in the sides 4 of the cover,

at the ends thereof, and enable the sides to be folded inwardly on the under side of the top 11 of the cover and also enable the ends 6 and the flaps 8 to be folded flat on the sides so that the cover may be collapsed or folded 55 in very small space. The cover may also be doubled and folded lengthwise to still more compactly arrange it if desired.

The sides and ends of the cover when the device is in use, engage over the sides and 60 ends of the basket as shown. To enable the top or central portion of the cover to clear the handle of the basket, the same is provided with a transverse slit 12 near its center and with slots 13 at its sides at right angles to and which communicate with said slit. The sides of the basket handle pass through the slots 13. The slit 12 is intermediate the ends of the slots 13. 65

The cover is also provided with a flap 14 70 which is attached thereto as at 15 on the upper side and near the center the said flap being adapted to extend across and cover the slit 12, and the contiguous portions of the cover which form the sides of said slit. 75

The cover may be readily attached to or removed from the basket and may be made of any suitable size, according to the size of the basket on which it is to be used.

It is believed that from the foregoing description, the nature and advantages of the invention will be readily apparent without requiring a more extended explanation and therefore the same has been omitted. However, I desire to have it understood that various changes in the construction and arrangement of parts may be resorted to when desired as fall within the scope of the appended claims. 80 85

Having described the invention, what is 90 claimed is:

1. A basket cover comprising sides, ends, and a central or top portion, said central or top portion having a straight transverse slit to clear a basket handle and having slots at 95 the ends of said slit to receive and clear the sides of the basket handle.
2. A basket cover comprising sides, ends, and a central or top portion, said central or top portion having a straight transverse slit 100

to clear a basket handle and having slots at the ends of said slit to receive and clear the sides of the basket handle, and a flap secured on said central or top portion of the cover 5 at a point spaced from one side of the slit and arranged to close over said slit.

In testimony whereof I affix my signature in presence of two witnesses.

JACOB F. BIXLER.
